UNITED STATES PATENT OFFICE

MIRKO MEDAKOVIC, OF ZAGREB, JUGOSLAVIA

SHOULDER REST FOR VIOLINS

Application filed December 23, 1930, Serial No. 504,315, and in Jugoslavia December 30, 1929.

This invention relates to a shoulder rest for violins and consists of a flat strip with scythe-shaped longitudinal edges with raised bearing cheeks on the transverse ends and fixing means on the transverse sides. The rest when in use only bridges the bearing corner of the violin and its wide transverse end rests on the shoulder of the player, its narrow transverse end on the collar bone near the neck of the player and the inner or shorter scythe-shaped longitudinal edge of the rest fits the neck of the player. Owing to its flat construction the rest is not in the way, not heavy and not very conspicuous.

An embodiment of the invention is illustrated by way of example in the accompanying drawing in which:

Fig. 1 shows a bottom plan view of a violin with the shoulder rest in position for use.

Fig. 2 is a side elevation of the violin.

Fig. 3 is a perspective view of the rest on enlarged scale.

The rest consists of a scythe-shaped strip *a* the width of which narrows gradually from one end towards the other, and which is of such length that it extends in arc shape above that corner of the bottom plate of the violin, which is used as shoulder rest, without touching this portion. The two transverse ends of the strip have raised bearing cheeks *b* and *c*. The broader end corner *b* of the scythe-shaped curved strip is on the left end, designed to rest on the shoulder of the player, and the outer edge of this end of the rest is rounded so that when being mounted it can be adapted to the left hand edge of the violin.

The narrower end cheek *c* of the rest fits on the opposite edge of the violin and is here fastened so that the rest, after having been fitted, extends from the shoulder of the player in arcuate shape to the collar bone near the neck. The height of the strip, formed by the rest owing to the end cheeks *b* and *c* is so selected that it equalizes the height from the shoulder to the chin of the player. The rest is pref-

erably made of wood, rubber, ebonite or similar material. Its bearing on the back is limited to the two narrow cheeks *b* and *c*, which bear on the non vibrating edge of the violin at the two supporting points. The attaching is effected by a screw threaded sleeve *d* at each end of the rest, similar to the attaching of the chin rest. Needless to say, that other attaching means might be employed. The outer surface of the rest is provided with a hollowing out *e*, the depth of which reduces towards the narrower end of the rest, in order to ensure a good seating on the shoulder of the player. Moreover this surface may be roughened or provided with a rough covering, for example a fluted rubber layer *f*, in order to prevent the instrument from sliding on the shoulder of the player. Soft supports are provided on the bearing points of the bridge and of the fastening means for protecting the edge of the violin. If the rest is properly used, the violin will be held tightly and securely between shoulder and chin upon the player exerting a slight pressure with his chin. The bottom plate does not touch the shoulder of the player and its vibration is not impeded in any way and at any point. The instrument sounds fuller and clearer when being played. The rest does not project at any point from the violin and is scarcely noticeable, it does not considerably increase the thickness and does not load the instrument on one side, as it bridges transversely over the bottom plate.

I claim:

1. A violin shoulder rest, comprising in combination a flat strip having two scythe-shaped longitudinal edges and two transverse upstanding ends, bearing cheeks on said transverse ends adapted to fit the lower edge of the violin so that said strip extends bridge-like over the bearing corner of the violin, and means on said cheeks adapted to fix said strip on the edge of the violin.

2. A violin shoulder rest, comprising in

combination a flat strip having two scythe-shaped longitudinal edges, two transverse upstanding ends of different widths, the under side of said strip having a recess increasing in depth from the short transverse end towards the long transverse end, a layer of rough material in said recess, supporting cheeks on each of said transverse ends adapted to fit the lower edge of the violin so that said strip extends bridgelike over the bearing corner of the violin, and means on said cheeks for fixing said strip to the edge of the violin.

In testimony whereof I affix my signature.
